UNITED STATES PATENT OFFICE

2,534,584

LATCH OPENER

Ruben Epstein, Brooklyn, N. Y., assignor to
H. Brinton Co., Philadelphia, Pa., a corporation
of Pennsylvania

Application August 26, 1949, Serial No. 112,517

8 Claims. (Cl. 66—111)

1

My invention relates to a combined latch-opener, needle protector and stop motion for knitting machines, and it is an object of the same to provide a device of improved character that shall not only open the needle latches and stop the machine if a needle is out of order but shall also move quickly out of the path of other needles, so as to avoid damage to or breakage of other needles. It is well known that the needles in a substantial segment of an entire needle circle may thus be damaged or broken otherwise.

Referring to the drawings, which are made a part of this application and in which similar reference characters indicate similar parts:

Figure 1 is a perspective view of part of a circular knitting machine, showing my invention;

Figure 2, an elevation of the device;

Figure 3, an elevation of the device, viewed from another side.

Figure 4, a top plan, with certain parts in a working position.

Figure 5, a top plan, with said parts in an idle position.

Figure 6, a section on line 6—6 of Figure 2.

Figure 7, a section on line 7—7 of Figure 2.

Figures 8 to 12, details of parts shown in other figures.

In the drawings, reference character 10 indicates a part of the machine that is fixed relatively to the needles and on which a bracket 11 is secured by a screw 12. The bracket has a post 13 on which is located a clamp 14 to which is secured a rod 15. A block 16 is mounted on the free end of rod 15, as by being threaded into the block and locked by a nut 17.

The block 16 is hollow and encloses a coil spring 18 which bears against a collar 19 slidably mounted on a bolt 20, held in place by a nut 21 at its lower end and having a collar 22 fixed to its upper end by a setscrew 22'. A spring 23 encircles an annular flange 23' depending from collar 22.

A hollow upward extension 24 on block 16 (Figs. 8 and 11) has a cam surface at 25 and two upwardly extending fingers 26, 27. A disk 28 (Figs. 6 and 10) on the bolt 20 is free to swing and is supported by a fixed collar 29 on rod 20. This disk 28 has an arm 30 extending from one side and a downwardly extending lug 31, (Fig. 6), the disk 28 and connected parts being shown upside down in Fig. 10. The spring 23 is attached to arm 30 at 32' and tends to rotate the disk clockwise.

The collar 19 is connected by a neck 33 to a block 19' that is mounted to swing and to move

2

along bolt 20 (see Fig. 9). This block has a vertical slot 33' leading to a bore 34 into which the stem 35 of the needle latch opener is inserted and is clamped in place by a screw 35' entered into a threaded aperture at 35' and which springs the parts together sufficiently to hold the stem in place. At its lower end the latch opener rod is bent at right angles to provide a part 36 lying near the needle circle, and is again bent at an angle of about 45° to provide a part 37 in the same plane with part 36, said part 37 tapering to a point situated so as to engage and open the latches of the needles in the circle.

A plate 38 of copper or other highly conductive material is fixed to the arm 30 (Figs. 10 and 12) by a bolt 39 with a nut 39' thereon. Insulating washers 40, 40' (Fig. 2) are interposed between said plate and arm, and the upper washer being in one piece with a sleeve 40'' that fits between the bolt and the arm 30 in a hole at 32. The lower washer fits on the sleeve 40''. A conductor 41 leads from the plate 38 to a stop motion of known type.

In the working position the latch opener is located as in Figs. 4 and 6 (solid line position), i. e., it has been moved by hand clockwise as far as possible into working position. In this movement it has also been forced down by the cam face 25 acting on neck 33, the parts being held in this position by reason of engagement of the flat upper surface of the neck with a flat face 42 at the end of the cam face 25. The disk 28 is rotated by its spring 23 until its lug 31 strikes finger 26, the movement of the contact plate 38 being so limited that it lies near the stem 35 but out of contact therewith.

The point 37 will now open all the latches of properly acting needles, but if a broken or bent needle approaches, it will cause the rod 35 and all parts fast thereto to turn counterclockwise to the idle position indicated in broken lines in Figs. 6 and 7. As soon as the rod 35 strikes the plate 38 a circuit will be closed, permitting current to flow from conductor 41 through bolt 39, plate 38 and rod 35 to the machine which is grounded, i. e., to the part 10 of Fig. 1 and thereby to actuate the stop mechanism of the machine, and the further movement of the latch opener assembly rotates the disk 28 and the parts carried thereby counterclockwise against the action of spring 23 to an idle position, the latch opener assembly also being rotated by its spring 18 and moving upward at the same time under control of cam 25 to its idle position. It will be seen that the stop motion is actuated promptly upon disability of a needle,

and that the latch opener is then quickly moved away from the needle row. Since a broken or bent needle frequently causes a smash-up that may destroy several dozen needles, the importance of removing the latch opener, which is also a needle feeler, to a position of safety will be evident.

It will be obvious to those skilled in the art that many changes may be made in the devices herein disclosed, all without departing from the spirit of the invention; and therefore I do not limit myself to what is shown in the drawings and described in the specification, but only as indicated in the appended claims.

Having thus fully described my invention, what I claim is:

1. In a latch needle knitting machine, the combination of a latch opener, means for holding it in an active position adjacent a row of needles, and means tending to move it substantially transversely of the needle row and also substantially axially of adjacent needles into an idle position.

2. A device as in claim 1, including an electrical conductor leading to a stop motion, and means in the path of the latch opener as it moves toward idle position, for closing a circuit to said conductor.

3. A device as in claim 2, wherein the movement of the latch opener continues after the circuit has been closed.

4. In a latch needle knitting machine, the combination of a latch opener, a post adjacent a row of needles, a spiral cam on said post, a follower for said cam said follower being attached to said latch opener, and resilient means for rotating said follower to move the latch opener away from the needle row and upward relatively to said post.

5. A device as in claim 4, wherein said cam has a flat at its lower end for restraining said follower in active position relatively to the needle row.

6. A device as in claim 4, including an arm on said post, insulated conducting means on said arm, a spring tending to rotate said arm toward the latch opener, and means for holding said conducting means out of contact with the latch opener during normal operation of the knitting machine.

7. In a latch needle knitting machine, the combination of a latch opener, a post adjacent a row of needles, a spiral cam on said post, a follower for said cam, said follower carrying the latch opener, a spiral spring surrounding the post and serving to rotate the follower and to move it upward along said post, an arm loosely mounted on the post, insulated conducting means on said arm for connection to a stop motion, a spiral spring surrounding said post and connected to said arm to rotate it toward the needle row, and a stop for limiting the rotation of the arm to maintain it out of engagement with the latch opener when the latter is in active position.

8. In a latch needle knitting machine, the combination of a latch opener, means for holding it in active position adjacent a row of needles, and means tending to move it to inoperative position by a motion transversely of the needle row and axially of the individual needles.

RUBEN EPSTEIN.
